UNITED STATES PATENT OFFICE.

PHILIP T. SHARPLES, OF ST. DAVIDS, PENNSYLVANIA.

CENTRIFUGAL SEPARATOR.

1,320,419.

Specification of Letters Patent.

Patented Nov. 4, 1919.

Application filed October 29, 1918. Serial No. 260,097.

To all whom it may concern:

Be it known that I, PHILIP T. SHARPLES, a citizen of the United States, and a resident of St. Davids, in the county of Delaware and State of Pennsylvania, have invented 5 certain Improvements in Centrifugal Separators, of which the following is a specification.

This invention comprises improved means 10 for separating substances of different specific gravities with high efficiency throughout variations in the amounts discharged, the relative volumes, and the viscosities of the constituents to be separated. At the same 15 time my invention makes it possible to construct a centrifugal machine in accordance with mathematical formulæ to function in a predetermined manner.

In the design of a centrifugal separator, 20 there are two considerations of prime importance to be taken into account. (1.) After the constituents have been separated into respective layers within the rotor, it is usually necessary that the constituents be 25 discharged separately, and that each constituent as discharged be as free from the other as in the centrifugal rotor. (2.) In order to gain high efficiency, each constituent should be subjected to centrifugal force 30 for a period of time, the extent of which is dependent upon the resistance of the other constituent to separation therefrom and upon the specific results which it is desirable to effect. In the case of a mixture of constituents A and B, the primary object of 35 the separation procedure is to get the A phase as free as possible from B, and the secondary object is to get the B phase as free as possible from A. If the separation 40 of the B from the A phase is more difficult to accomplish than the separation of the A from the B phase, then the A phase should be subjected to the separating force for a much longer period than the B phase. 45 But, conversely, if the separation of the B from the A phase is very easily accomplished, both objects of the procedure can be more nearly attained by subjecting the B phase to centrifugal force for a somewhat 50 longer period than the A phase.

In practice the period of time during 55 which centrifugal force acts on a substance is dependent upon the amount of the substance held in the rotor, and the rate of displacement—*i. e.*—the rate of feeding and discharge. It is apparent, therefore, that

the period of time during which each constituent is subjected to centrifugal force is controlled by the respective rates of discharge of the constituents and the relative 60 volumes of the constituents held in the rotor. Obviously the relative amounts of the constituents held in the rotor are not in any way dependent upon the rates of discharge. The ratio between the amounts of the constituents held in the rotor is limited both 65 for maximum and minimum by the mechanical considerations necessary to effect separate discharge.

Only by properly taking into account the 70 points discussed above can a rotor be designed to function properly (to yield desired results at the maximum rate of displacement) for satisfactorily handling the largest volume of material in a given time. 75

Any means for insuring a correct ratio 80 of the amounts of constituents in the rotor will insure at the same time correct functioning. The determination of just what is the correct ratio for any given case can be gained by a consideration of the relative 85 amounts of the constituents in the substance to be centrifuged, but an accurate determination is necessarily empirical. When the ratio has been determined, it is necessary to know how to construct a centrifugal rotor that will so function as to 90 maintain this ratio.

Heretofore, it has been practicable to design centrifugal rotors to yield a given ratio 90 of constituents held in the rotor for a given capacity (rate of combined discharge), a given ratio of amounts discharged, and a given viscosity of constituents. The formulation of this design, although somewhat dependent upon relative specific gravities of the constituents, has been in the main purely empirical. It has been characteristic of all 95 centrifugal rotors designed heretofore that the ratio of constituents held in the rotor has been decidedly altered by a change in capacity, a change in the relative rates of discharge, or a change in the viscosity of the constituents. The aforesaid variation in ratio has frequently been so great as to go 100 beyond the limits required for the separate discharge of constituents. For example, a rotor designed to maintain a correct ratio when two constituents each discharge at the rate of 5 barrels per hour, will cause a discharge of a considerable proportion of one 105 constituent with the other when the rate of

110

discharge of one constituent is increased to 10 barrels per hour or is reduced to 1 barrel per hour.

It is a primary object of my invention to 5 maintain the ratio of constituents held in the rotor substantially constant despite large variations in the capacity, the relative rates of discharge, and the viscosity of the constituents. At the same time the design of 10 the rotor is no longer affected by any empirical considerations, but is founded upon the mathematics of hydrostatic pressure and centrifugal force.

By maintaining a constant ratio in the 15 rotor, the relative periods of time during which the respective constituents are subjected to centrifugal force are maintained constant.

To explain how my invention effects these 20 results, it is desirable to state that the relative amounts of constituents held in the rotor are determined by the fact that the hydro-static pressure of the constituents must balance at the surface where the separated constituents 25 come in contact before they are discharged.

Hydro-static pressure in a liquid subjected to centrifugal force is a function of the angular velocity, the specific gravity of the constituents, the radial distance of the contact 30 surface mentioned above from the axis of rotation, and the radial distance from the axis of rotation of the surface where the liquid comes nearest to the axis of rotation.

It is the last mentioned factor that is so 35 variable in the rotors heretofore designed and a variation in this factor obviously causes variation in the distance from the axis of rotation to the surface where the constituents come in contact, thus changing the 40 ratio of constituents held in the bowl, changing the relative periods of time during which the constituents are subjected to centrifugal force, reducing the efficiency of separation, and changing the character of the results.

45 The point where a constituent comes nearest to the axis of rotation is hereafter termed the "discharge surface" of the constituent. It is evident that the discharge surface is in practice always nearer the axis of rotation than is the weir which controls it. The difference is the depth of the crest, and for 50 a weir of given width (concentric with the axis of rotation) and a given length (parallel with the axis of rotation) is dependent upon the rate of discharge and the viscosity of the constituent. Inasmuch as the functioning of the rotor is dependent upon the 55 distances of the relative discharge surfaces from the axis of rotation, it is obvious that the design of a rotor in which the depths of the crests are comparatively great involves a corresponding correction in the determination of the distances of the weirs from the axis of rotation. This correction involves 60 so many unknown factors that the design is

perforce empirical. If, on the contrary, the depths of the crests are in practice negligible, the discharge surfaces may be considered as coincident with the weirs and the dimensional characteristics of the rotor may 70 be computed with mathematical accuracy.

If the depth of a crest is appreciable under any given set of conditions, it follows that a change in these conditions will cause an appreciable change in the depth of the 75 crest. This is the explanation of the failure of the usual rotor to function properly under changing conditions.

In accordance with my invention, in its preferred form, the separated constituents 80 are discharged over annular weirs having knife edges concentric with the axis of rotation; the weirs in a rotor being similar in character with edges concentric to the layers of the separated constituents to be discharged thereover so that the respective constituents shall be subject to conditions which maintain their relations throughout changes in the rates of discharge or viscosities, and such weirs being provided by rings one or 85 both of which can be changed to alter the discharge radius in accordance with the characteristics of the constituents to be separated. But it will be understood that these changeable rings are not essential, particularly where the densities of the substances under treatment do not change, and that the contours of the weirs may vary from the preferred concentricity, improvement being 90 effected by increasing the radii of the weirs substantially over those heretofore used.

Characteristic effects of my improvements are the production of desired crests of maximum widths and minimum depths, which do not change substantially with changes in the 105 proportions of the constituents to be separated, the capacities, or the viscosities, and do not substantially change the radius of conjunction of the layers of separated constituents, thereby maintaining a constant 110 ratio of amounts of constituents held in the rotor.

The characteristic features of my invention are set forth in the following description and the accompanying drawings embodying a form thereof.

In the drawings, Figure 1 is a broken section view of a centrifugal separator illustrating a form of my improvements; Fig. 2 is an enlarged broken sectional view of the top 120 of the bowl of Fig. 1; Fig. 3 is a sectional plan view taken on the line 3-3 of Fig. 2; Fig. 4 is a sectional view taken on the line 4-4 of Fig. 2; and Fig. 5 is an irregular sectional view through a bowl stem illustrating modifications in construction.

The mechanism illustrated comprises the frame 1 providing a case 2 in which the bowl 3 having the neck 4 is suspended and revolved by the spindle 5 coupled to the neck, 130

the bowl being fed through its bottom inlet 6 by the nozzle 7 supported by the case.

In accordance with my invention, in its preferred form, the weirs or dams over 5 which the separated constituents flow comprise the ring 8, having the inner narrow lip or knife edge 8' concentric with the axis of rotation and the outer edge 8'', and the ring 9 having the narrow lip or knife edge 9' 10 concentric with the axis of rotation, providing means for controlling the discharge of the constituents which have been separated in the bowl.

The lighter constituent, after passing 15 through the ring 8, over its inner edge 8', is discharged outwardly by way of the channel 8^a concentric with the edge 8' and the passage 10 in the neck 4 to the receptacle 11, the outlet channels being of such cross sec- 20 tional area and distance from the axis of rotation as to offer no obstruction to the discharge over the edge 8'. The heavier constituent flows over the edge 8'' of the ring 8 and through the inwardly inclined 25 passage 12 of annular cross section to the annular channel 13 surrounding the neck 4, whence it is discharged over the over- hanging edge 9' of the ring 9 and into the receptacle 14.

30 The ring 8 is provided with a concentric collar 15 which forms the outer wall of the channel 8^a and is adapted to be screwed on the bottom of the neck 4, permitting the substitution of rings or weirs of different di- 35 mensions proportioned to different condi- tions of characteristics of the constituents to be separated, if desired. The ring 9 lies within a collar 16 fixed on the top of the bowl and is held in place by a ring 17 which 40 screws on the collar and has a flange 17' which engages such ring 9, providing for the substitution of controlling rings or weirs of different internal diameters proportioned to different conditions of use.

45 Wings 18 are fixed to the ring 8 and the collar 15 to provide means in the top of the bowl for imparting rotary motion to the fluid.

As the edges 8' and 9' are full circles con- 50 centric with the strata occupied by the constituents in the bowl, being placed at the radial distances for effecting the control desired, the change in the depths of the constituents flowing over such edges will be 55 negligible or a minimum, varying unsub- stantially with such slight changes as may take place in the discharge or inner surface of the lighter constituent and the place of division between the edges 8' and 8'' of the 60 separated constituents in the bowl.

While the ideal construction comprises full annular knife edges concentric with the axis of rotation for controlling the discharge of the different constituents, this construc- 65 tion may be modified within the scope of my

invention and improved results obtained over previous devices, as by the use of outlets oblong in the direction of an arc having its center in the axis of rotation. A form of such modification is illustrated in Fig. 5, 70 where the stem 4 is provided with discharge passages 10' and 12' for constituents of different densities, which passages are, in cross section, annular segments concentric to the bowl and which may discharge directly to 75 the receptacles 11 and 14.

Having described my invention, I claim:

1. In a centrifugal separator, a revoluble bowl provided with means comprising outlets and weirs for effecting the discharge 80 of separated constituents with negligible depths at said weirs.

2. In a centrifugal separator, the combi- 85 nation with a frame, of a bowl, and means for supporting said bowl vertically in rev- oluble relation to said frame said bowl pro- vided with means for discharging sep- arated constituents and maintaining a sub- stantially constant ratio between the con- stituents held in said bowl throughout 90 variations in the quantities discharged.

3. In a centrifugal separator, the combi- 95 nation with a frame, of a bowl, and means for supporting said bowl vertically in revoluble relation to said frame said bowl pro- vided with means for discharging sep- arated constituents and maintaining a sub- stantially constant ratio between the con- stituents held in said bowl throughout 100 changes in the relative rates of discharge.

4. In a centrifugal separator, the combi- 105 nation with a frame, of a bowl, and means for supporting said bowl vertically in rev- oluble relation to said frame said bowl pro- vided with means for discharging separated constituents and maintaining a substantially constant ratio between the constituents held in said bowl independently of the viscosity 110 of said constituents.

5. In a centrifugal separator, a revoluble 110 bowl having controlling weirs substantially concentric with the axis of revolution.

6. In a centrifugal separator, a revoluble 115 bowl having weirs with narrow edges for controlling the discharge of separated constituents.

7. In a centrifugal separator, a revoluble 120 bowl provided with outlets and weirs for controlling the discharge of separated constituents so that the distances of the nearest points of the discharging constituents to the axis of revolution shall be in substan- tially constant ratio throughout changes in the rate of discharge.

8. In a centrifugal separator, a revoluble 125 bowl having outlets and rings with edges of different diameters for controlling the discharge through said outlets.

9. In a centrifugal separator, a revoluble 130 bowl having outlets for separated constit-

- uents and changeable weirs for controlling the discharge of separated constituents through said outlets.
10. In a centrifugal separator, a revoluble bowl having outlets, substantially concentric rings of different diameters for controlling the discharge through said outlets, and means for permitting the ring of smaller diameter to be changed.
- 10 11. In a centrifugal separator, a revoluble bowl having outlets, substantially concentric rings of different diameters for controlling the discharge through said outlets, and means for permitting the ring of 15 larger diameter to be changed.
12. In a centrifugal separator, a revoluble bowl having a substantially concentric channel and ring in combination with a passage for discharging a separated constituent under control of said ring.
- 20 13. In a centrifugal separator, a revoluble bowl having discharge passages oblong in cross section transversely to the axis of revolution for separated constituents of different densities and weirs for controlling the flow of constituents through said passages, said weirs extending in the direction of arcs struck therethrough with the axis of revolution as a center.
- 25 14. In a centrifugal separator, a revoluble bowl provided with outlets and weirs placed at the radial distances for effecting the desired discharge control of separated constituents through said outlets, said 30 weirs having approximately the largest practicable dimensions transversely to the direction of flow of the discharging constituent.
15. In a centrifugal separator, a revoluble bowl provided with outlets and weirs 40 adapted for producing approximately the maximum widths and the minimum depths of crests for the discharging separated constituents.
16. In a centrifugal separator, the combination with a frame, of a bowl, and means for supporting said bowl in revoluble relation to said frame, said bowl having outlets for discharging substances of different specific gravities separately and 45 means for maintaining a substantially constant distance between the axis of rotation of said bowl and the discharge surface of the substance of least specific gravity notwithstanding changes in the relative rates 50 of discharge of said substances.
17. In a centrifugal separator, the combination with a frame, of a bowl, and means for supporting said bowl in revoluble relation to said frame, said bowl having outlets for discharging substances of different specific gravities and means for maintaining a substantially constant ratio between the distances of the discharge surfaces 55 from the axis of rotation notwithstanding changes in capacity, relative rates of discharge and viscosity of said substances.
- In testimony whereof I have hereunto set my name this 26th day of October, 1918.
- P. T. SHARPLES.
